UNITED STATES PATENT OFFICE.

JULIUS T. ROSENHEIMER, OF NEW YORK, N. Y.

DESIGN FOR A FOLDING CARD.

SPECIFICATION forming part of Design No. 26,581, dated February 2, 1897.

Application filed December 21, 1896. Serial No. 610,545. Term of patent 3½ years.

To all whom it may concern:

Be it known that I, JULIUS T. ROSENHEIMER, a citizen of the United States, and a resident of New York city, county and State of New York, have invented and produced a new and original Design for Folding Cards, of which the following is a specification, reference being had to the accompanying drawing, which represents a perspective view of my newly-designed folding card.

The leading feature of my design consists in a folding card upon one leaf of which is represented an oval figure with a pair of transverse ridges, a series of vertical tapering bars, a folded cover, and a border composed of horizontal lines and broken vertical lines.

a b represent two leaves of a folding card.

Upon the upper end of leaf *a* is represented an oval figure *c*, across which extend a pair of transverse ridges *d* and a number of vertical tapering bars *e*. Upon the lower end of leaf *a* is represented a folded cover *f*. Upon each side of leaf *a* is represented a border composed of horizontal lines *j* and broken vertical lines *k*. On leaf *b* is represented a cupid *g*, a section of a leaf *h*, a pair of twigs *i i*, and a border *l*.

What I claim is—

The design for a folding card, substantially as herein shown and described.

J. T. ROSENHEIMER.
